UNITED STATES PATENT OFFICE

FRIEDRICH OTTENSTEIN, OF NUEREMBERG, GERMANY

ELECTRIC TOY RAILWAY TRACK

Application filed June 5, 1931, Serial No. 542,439, and in Germany June 24, 1930.

In the known switches for toy railway tracks the switch levers are always unremovably fixed at the side of the switch, so that with any otherwise possible arrangement of the rails, for instance in the case of larger point lay-outs for stations and shunting stations, the switch lever becomes a disturbing constructional element. Furthermore, through the fixed arrangement of the switch levers the known points form large, bulky pieces.

These disadvantages are overcome by the present invention, which firstly enables the switch lever to be attached by means of a link member for the switch operating mechanism in a releasable manner to the support for the latter at either side of the switch, and secondly enables the switch to be taken apart to such an extent that, assuming symmetrical rail sections to be used, a switch may be put together for right-hand or left-hand branches from the same separate parts, with the interchange of only a few small replacement pieces.

In the accompanying drawing a constructional example of the invention is illustrated, Fig. 1 showing a plan view of the switch, Fig. 2 the switch in longitudinal section on line A—A of Fig. 1,

Fig. 3 the switch operating mechanism according to Fig. 1, as seen from below,

Fig. 4 the switch operating mechanism with a signal lamp disposed in front of it in side elevation,

Fig. 5 the switch signal lamp in side elevation,

Fig. 6 a switch tongue in plan view and side elevation,

Fig. 7 the heel pivot plate for the switch tongue, as seen from above and from below, and

Fig. 8 the switch tongue controlling means in detail to an enlarged scale.

Over the supporting structure consisting substantially of a middle sleeper 1 and two T-pieces 2, 3 of U-shaped bent sheet metal suitably positioned with respect thereto, a curved track branches off from a straight track. The straight track consists of a long straight length of rail 4 and of two shorter

straight lengths of rail 6, 7 which lie in alignment with the switch tongue 8. The curved track is formed by a longer bent rail 5 and by two shorter curved lengths of rail 9, 10 disposed one behind the other and the other switch tongue 11. The rails are secured by screw clips 14 on the sleepers 1, 12 and 13 and on the T-pieces 2, 3. The points of the switch blades 8, 11 are made in such a manner that they cannot become bent by the wheels striking them, thus reliably preventing derailing. The rail pieces 7, 10 have their ends inserted in slots 15 (Fig. 7) of solid fitting pieces 16, 17 made of insulating material. The rail pieces 6, 9 also each have one end inserted in such slots, while the other end is held by clips 14 on the sleepers 12, 13. The fitting piece 16 at the same time forms the securing member for the pivoted switch blades 8, 11 and for a live rail 18 disposed between them and also for a wedge-shaped current conducting tongue 19 disposed within the switch. The switch blades 8, 11 are pivoted in cup-shaped depressions 20 of the fitting piece 16 (Fig. 7, in which disc-shaped pins 21 at the heels of the blades engage (Fig. 6).

Each of the laterally extending arms of the T-piece 2 is adapted to be connected by a screw connection 22 to a sleeper-like extension 23. On this extension 23 two bearing pedestals 24 (Fig. 4) are disposed, between which is journaled on a shaft 25 a two-armed switch lever 26, the upper arm of which carries a disc-shaped weight 27, while the lower arm extends through a slot 28 in the extension 23 (Figs. 1 and 3) and is connected to a link 29 disposed in the interior of the sleeper extension 23. The link 29 has a U-shaped crank 30 (Fig. 3) and is pivotally connected to a lever arm 31 adapted to swing within the T-piece 2. The limbs 30a, 30b of the crank 30 act as stops for a pin 32 of a switch signal lamp 33 (Figs. 1, 3, 5). The lamp 33 is provided with a pivot pin 34 which is mounted in the web of the extension 23. The stop pin 32 extends through an arcuate slot 35 extending around the hole of the pivot pin 34, which slot is of such a length that the lamp 33 can be turned

through 90°. The lever arm 31 forms part of an arrangement of crossed levers capable of turning about a pin 36 fixed in the T-piece 2 (Figs. 3 and 8), the arms 37, 38 of which form a straight line with each other and lie at right angles to the arm 31, while the short arm 39 which is provided with a central elongated slot 40 forms an extension of the arm 31. To the ends of the arms 37 and 38 arms 41, 42 are pivoted, which latter arms each extend through an opening in the adjacent side walls of the T-piece 2 and each have a helical compression spring 43, 44 slipped over them. The helical springs 43, 44 bear at one end against the pivot connection of the pivoted arms and at the other end against the side walls of the T-piece 2 and, through being stressed, impart to the crossed lever arrangement 31, 37, 38, 39 such a torque that the crossed lever arrangement remains each time in the position into which it has been rocked. Into the slot 40 (Figs. 8, 3) of the arm 39 there extends the operating pin 45 of a coupling bar 46 made of insulating material which forms a parallel guide for the switch blades 8 and 11. The said blades are connected to the bar 46 by bolts 48 which are guided in slots 47 in the T-piece 2.

The switch is manipulated and acts in the following manner:

When the switch is in the position shown in Fig. 1 the straight piece of track 4 is clear and the branch 5 is blocked. When the branch line is to be cleared and the straight track is to be blocked, the switch lever 26 is rocked into the position B shown in Fig. 4 in dot and dash lines. This causes the link 29 to be pushed further into the arm extension 23 and the crossed lever arrangement 31, 37, 38, 39 to be moved into the position C shown in broken lines in Fig. 3. The limb 30a strikes against the stop pin 32 of the lamp 33, forcing the said pin against the other end of the arcuate slot 35, thus causing the lamp 33 to be turned through 90° into the position D shown in dot and dash lines in Fig. 4. Through the change over of the crossed lever arrangement the coupling bar 46 is also displaced and the switch blades 8, 11 are changed over in such a manner that the curved track, that is the branch 5, becomes clear. During the change over of the crossed lever arrangement the compression springs 43, 44 are stressed until the arms 37, 38 and the pivoted arms 41, 42 lie in a straight line. After the dead centre position has been passed, the springs 43, 44, on expanding, force the crossed lever arrangement rapidly into the other extreme position and hold it in this new position. Should it be impossible to lay the switch piece in the manner shown, as for instance there is some obstacle at a place at which the extension 23 would lie, the extension together with the switch lever 26, the

lamp 33 and the link 29 can instead be fixed to the other arm of the T-piece 2, the link 29 being connected to the lever arm 31 from this side, as shown in dot and dash lines by E in Fig. 3.

What I claim is:

1. For use at a turn-out of a toy railway track a switch comprising supports, switch blades, means adapted to be attached in an easily releasable manner on the right-hand or left-hand side of the turn-out for changing over the said switch blades, rail pieces and members for fixing the said rail pieces to the supports, so as to be capable of being easily released.

2. For use at a turn-out of a toy railway track a switch comprising a support, switch blades, means adapted to be disposed on the right-hand or left-hand side of the turn-out for changing over the said switch blades, rail pieces, members for fixing the said rail pieces to the support, so as to be capable of being easily released, a supplementary part for supporting the blade change-over means and means for releasably attaching the said supplementary part to the support on the right-hand or left-hand of the turn-out, so as to form an extension of the support on one side thereof, as and for the purpose set forth.

3. A switch as claimed in claim 1 and comprising a switch signal lamp, a link member for operating the switch blades and for turning the signal lamp, a rectangular cranked part in the said link member and a stop pin on the lamp adapted to be displaced by two opposite limbs of the said cranked part, as and for the purpose set forth.

4. A switch as claimed in claim 1 and comprising a bar for coupling the switch blades, a pin on the said bar, a link member, a crossed lever arrangement having four arms at right angles to one another, one of which is in operative engagement with the link member, a slotted guide for the said pin in the arm forming the extension of the aforesaid arm, rocking members pivoted to the ends of the other two arms of the crossed lever arrangement which are at right angles to the two first-named arms and compression springs on said rocking members for securing the whole switch operating device in the desired position, as and for the purpose set forth.

In testimony whereof I have signed my name to this specification.

FRIEDRICH OTTENSTEIN.
